(57) **CLAIM**

The ornamental design for a combinable electronic vaping device, as shown and described.

DESCRIPTION

FIG. 1 is a perspective view of a new design for a combinable electronic vaping device.

FIG. 2 is a top view of the combinable electronic vaping device of FIG. 1.

FIG. 3 is a bottom view of the combinable electronic vaping device of FIG. 1.

FIG. 4 is a left side view of the combinable electronic vaping device of FIG. 1.

FIG. 5 is a right side view of the combinable electronic vaping device of FIG. 1.

FIG. 6 is a front view of the combinable electronic vaping device of FIG. 1.

FIG. 7 is a back view of the combinable electronic vaping device of FIG. 1.

FIG. 8 is a perspective view of the combinable electronic vaping device of FIG. 1, in a first state of use configuration.

FIG. 9 is a top view of the first state of use configuration of FIG. 8.

FIG. 10 is a bottom view of the first state of use configuration of FIG. 8.

FIG. 11 is a left side view of the first state of use configuration of FIG. 8.

FIG. 12 is a right side view of the first state of use configuration of FIG. 8.

FIG. 13 is a front view of the first state of use configuration of FIG. 8.

FIG. 14 is a back view of the first state of use configuration of FIG. 8.

FIG. 15 is a perspective view of the combinable electronic vaping device of FIG. 1, in a second state of use configuration.

(Continued)

FIG. 16 is a top view of the second state of use configuration of FIG. 15.

FIG. 17 is a bottom view of the second state of use configuration of FIG. 15.

FIG. 18 is a left side view of the second state of use configuration of FIG. 15.

FIG. 19 is a right side view of the second state of use configuration of FIG. 15.

FIG. 20 is a front view of the second state of use configuration of FIG. 15.

FIG. 21 is a back view of the second state of use configuration of FIG. 15.

FIG. 22 is a perspective view of another embodiment of the new design for a combinable electronic vaping device.

FIG. 23 is a top view of the combinable electronic vaping device of FIG. 22.

FIG. 24 is a bottom view of the combinable electronic vaping device of FIG. 22.

FIG. 25 is a left side view of the combinable electronic vaping device of FIG. 22.

FIG. 26 is a right side view of the combinable electronic vaping device of FIG. 22.

FIG. 27 is a front view of the combinable electronic vaping device of FIG. 22; and,

FIG. 28 is a back view of the combinable electronic vaping device of FIG. 22.

Broken lines in the drawings depict environmental structure that forms no part of the claimed design and features of the combinable electronic vaping device that form no part of the claimed design.
